213,161

FRUIT SEGMENT SQUEEZER

Royal E. Coons, 306-A Park St., Alhambra,
Calif. 91801

Filed Feb. 15, 1968, Ser. No. 10,591

Term of patent 14 years

U.S. Cl. D89—1
Int. Cl. D7—02

FIG. 1 is a side elevational view of a fruit segment squeezer showing my new design in open position;

FIG. 2 is a top plan view;

FIG. 3 is a bottom plan view;

FIG. 4 is a front elevational view;

FIG. 5 is a rear elevational view; and

FIG. 6 is a side elevational view with the squeezer in closed position.

I claim:

The ornamental design for a fruit segment squeezer, as shown.
